DISPLAY HOLDER

Arthur C. Handler and Morris H. Wansky, Akron,
Ohio; said Wansky assignor to said Handler

Application April 19, 1934, Serial No. 721,411

6 Claims. (Cl. 24—81)

This invention relates to a new and useful display holder which can be used for displaying a number of different kinds of merchandise in various ways.

5 The object of the invention is to provide an economical, compact display holder which will hold the merchandise or article to be displayed in a manner to provide for a maximum unobstructed view of the article and at the same 10 time to provide for attachment of the display holder to a fixture or box in a simple manner. The merchandise, holder and fixture can be easily and quickly assembled or taken apart.

The display holder can be used to great advantage in retail stores where merchandise is stacked in boxes on shelves and it is desired to display one sample of the item contained in the box.

One of the objects of the invention is to provide a display holder for attaching to shoe boxes in a retail store so that one shoe from each box can be displayed on the outside of the box. This saves a great deal of the salesman's time in locating the proper style shoe. This arrangement 25 is even a greater time saver during special sales when extra sales people are used who are not entirely familiar with the stock of merchandise.

It is a well known and accepted principle of merchandising that the proper displaying of a 30 certain line of merchandise so that a customer can look over the complete assortment and choose the style, quality and price item in which he is interested, automatically increases sales, with less sales resistance and with quicker 35 summation.

The display holder herein described can be quickly and easily attached to the end of a shoe box at its top edge, a shoe placed in the holder and the lid of the shoe box replaced. The 40 holder is provided with a groove for a style and price card and is constructed so that any shoe on display is automatically displaced from its position if it is desired to remove a lower box.

Figure 1 is a side view of the holder 10 attached to the shoe box 12 with box lid 13 in position on the box, shoe 11 attached in display position on the holder 10, style and price tag 14 positioned in the holder 10, and lower tier of boxes 15.

50 Figure 2 is a front view of Figure 1 showing holder 10, shoe 11 and style and price tag 14.

Figure 3 is a side view showing the same parts as Figure 1 except lower box 15 is partly removed from the stack. It shows the action of 55 hinge 16 which allows the shoe 11 to automatically

displace itself from its original position when the next lower box is being removed. After the box 15 is removed from the stack shoe 11 returns to its original position.

Figure 4 is a side view of the holder 10 attached to the shoe box 12 with the shoe box lid 13 in position and style and price card 14 in position. This shows the position of the holder when shoe has been detached.

Figures 5 and 6 show a different embodiment, 10 the clamp in this embodiment being adjustable. Figure 5 is a side view and Figure 6 is a cross section on line 6—6 of Figure 5.

The holder is made of light gauge material formed as in Figures 1, 2, 3 and 4 with a clamp 15 18 that clinches over the inside front end 19 of shoe box 12. The material is formed at this point in an inverted U-shape to pass over the edge of the box, under the lid and return on the outside surface of the shoe box. Another 20 U is formed at point 20 to allow a space 21 for the front outside edge of lid 13 to position itself. Groove 22 is formed for the purpose of providing a space for a display card. Hinge 16 allows for an up and down arc movement of the shoe while 25 lower adjacent boxes are being moved and also permits the arm 10 to fold down out of the way when merchandise is not displayed on the holder.

Arm 10 in Figures 1, 3 and 4 extends from the 30 hinge 16 and forms an inverted lip 23. This lip holds the article to be displayed.

In the second embodiment, Figures 5 and 6, slider 17 with attachment arm for supporting the merchandise, is provided for the purpose of adjusting the length of the holder to the size of the article displayed at the point of attachment. This slider is arranged in the form of a friction 35 clamp and can be moved forward or backward on the arm 10 to allow for shortening or lengthening the hold on the article displayed.

While we have explained the general principles involved in this holder, it will be seen that the details can be varied and still remain within the general scope of our invention.

Having described our invention, what we claim is

1. In a display holder, the combination with a clamp, a groove shaped receptacle to receive a 50 display card, and an extended arm with an adjustable friction slide clamp adjacent thereto.

2. In a display holder, the combination with a clamp, a groove shaped receptacle to receive a display card adjacent thereto, an inverted lip 55

arm to hold the merchandise, and a rotary connection between the receptacle and arm.
3. In a display holder the combination with a clamp, a groove shaped receptacle to receive a display card adjacent thereto, an arm, and a rotary connection between the receptacle and arm.

4. In a display holder, the combination with a clamp, a groove shaped receptacle to receive a display card adjacent the clamp, an arm, a friction slide on the arm, and a rotary connection between the receptacle and arm.

5. In a display holder, the combination with an inverted U-shaped spring friction clamp, an adjacent U-shaped groove receptacle to hold a display card, an extended arm, and a rotary connection between the receptacle and arm. 5

6. In a display holder, the combination with an inverted U-shaped friction spring clamp arranged for inside attachment to a lidded box, an arm, and a rotary connection between clamp and arm. 10
